(57) **CLAIM**

The ornamental design for a tire, as shown and described.

DESCRIPTION

FIG. 1 is a front perspective view of the tire showing my new invention;

FIG. 2 is a front elevation view thereof;

FIG. 3 is an enlarged partial front elevation view thereof;

FIG. 4 is a right side elevation view thereof; and,

FIG. 5 is a left side elevation view thereof.

The dashed broken line represents the border between the claimed tire well and the unclaimed interior of the tire, and forms no part of the claimed design.
